(57) **ABSTRACT**

The invention relates to a method and apparatus for installing a propeller assembly (1) in an opening (9) in the bottom (8) of a swimming vessel and for removing the propeller assembly (1) from the opening (9). The propeller assembly (1) comprises an underwater section (2) including the actual propeller and a top section (3) inside the vessel, between which is fitted a flange element (4) for tightly sealing the opening (9). The apparatus comprises a hoisting chamber (7), which is fitted in the opening (9) in the bottom of a vessel, extends inside the vessel to above waterline and surrounds the top section (3) of the propeller assembly. The apparatus further includes guide elements for guiding the propeller assembly (1) during the course of lifting or lowering. In the method, the propeller assembly (1) is lifted away by way of the top of the hoisting chamber (7) after clampings of the propeller assembly (1) to the hull of a vessel are unfastened and hoisting means (12) are secured to the propeller assembly (1). Installation proceeds in a reversed order.

SWIMMING VESSEL**

**CROSS-REFERENCE TO RELATED
APPLICATION**

This application is a Division of application Ser. No. 09/117,135, filed Jul. 23, 1998 now U.S. Pat. No. 6,067,697.

BACKGROUND OF THE INVENTION

The present invention relates to a method as set forth in the preamble of claim 1 for removing a propeller assembly from and for mounting the same in an opening in the bottom of a swimming vessel as well as to an apparatus as set forth in the preamble of claim 4.

SUMMARY OF THE INVENTION

An object of the present invention is to provide an improved and relatively simple and reliable method and apparatus for removing and mounting a propeller assembly for maintenance, repairs or replacement without having to bring the vessel to dock. This is particularly important in connection with various rig platforms used by off-shore industry, said rigs being often designed to remain stationary for long periods of time, e.g. up to 20 years. In the prior art, the propeller assemblies have been installed and removed from outside the vessel by means of various hoisting mechanisms. In a normal case, these necessitate the use of a diver for securing the hoisting cables to the propeller assembly. A drawback in such externally performed removal and installation of a propeller assembly is that such operations are highly dependent on weather conditions. In poor weather, a diver cannot be used for such operations for reasons of safety.

In order to achieve the above-described object of invention, a method of the invention is characterized by what is set forth in the characterizing clause of claim 1. On the other hand, an apparatus of the invention is characterized by what is set forth in the characterizing clause of claim 4.

BRIEF DESCRIPTION OF THE DRAWINGS

The invention will now be described with reference made to the accompanying drawings, in which FIGS. 1-3 depict one apparatus of the invention at various stages of removing a propeller assembly.

**DETAILED DESCRIPTION OF THE
PREFERRED EMBODIMENTS**

FIGS. 1-3 illustrate an apparatus for removing a propeller assembly 1 from and for mounting the same in an opening 9 in a vessel bottom 8. The illustrated propeller assembly 1 comprises an underwater section 2, including the actual propeller, as well as a top section 3 inside the vessel, between which is a flange element 4 for tight sealing of the opening 9. The propeller is coupled through the intermediary of appropriate gear means to a gear shaft 5, which is in turn connected to power means 6, e.g. an electric motor or a diesel engine. In the depicted embodiment, the gear shaft 5 is removable. The opening 9 is associated with a hoisting chamber 7, extending upwards inside the vessel to above waterline and having its bottom portion provided with a passage 13 for the gear shaft 5. The hoisting chamber 7 is

designed to be watertight. Furthermore, inside the hoisting chamber 7 are included guide elements, not shown, for holding the propeller assembly 1 in a correct position during lifting and lowering.

5 The following describes the operations for removing and lifting the propeller assembly 1 from the opening 9. The description is but an example of one preferred implementation and is by no means intended to limit the scope of protection defined in the claims for the invention.

10 Firstly, the gear shaft 5 is disengaged from between the top section 3 of the propeller assembly 1 and the power unit 6, at the same time removing pertinent electrical wires and hydraulic tubes and other possible pipes. Next, the passage 13 is sealed with a watertight flange 11 (FIG. 2) and the top section 15 3 of the propeller assembly 1 is covered with a watertight protective casing 10. The next step is to unfasten the clamping elements which secure the propeller assembly to the hull of a vessel and to fasten hoisting cables 12 to the propeller assembly 1 and to let the water in the hoisting chamber 7. Finally, the propeller assembly 1 is lifted by way of the top of the hoisting chamber 7 and carried away for necessary procedures. Installation of the propeller assembly 1 into the opening 9 proceeds in a reversed order. The removal of water remaining in the hoisting chamber 7 during 25 the course of installation can be effected by means of conventional pump equipment.

The apparatus can be subjected to a number of modifications without departing from the scope of protection defined in the claims for the invention. For example, the top section 3 of the propeller assembly 1 could be originally designed to be totally resistant to pressure water, whereby the use of a separate protective casing 10 is not necessary.

What is claimed is:

1. An apparatus for installing a propeller assembly in an opening in the bottom of a swimming vessel and for removing the propeller assembly from the opening, said propeller assembly comprising an underwater section including the actual propeller and a top section inside the vessel and coupled to power means driving the propeller assembly, said sections having therebetween a flange element for tightly sealing the opening, characterized in that the apparatus comprises a hoisting chamber, which is mounted around an opening, in the bottom of a vessel, extends inside the vessel to above the waterline and surrounds the top section of the propeller assembly, and means for lifting the propeller assembly away by way of the top of the hoisting chamber, and in that the power means are located outside the hoisting chamber, and coupled by means of a removable gear shaft to gear means included in the top section of the propeller assembly for transmitting power further to the actual propeller, said gear shaft being adapted to extend through a passage included in a wall of the hoisting chamber, said passage being sealable by means of a watertight sealing element.

45 2. An apparatus as set forth in claim 1, characterized in that it further includes a watertight protective casing to be mounted over the top section of the propeller assembly.

50 3. An apparatus as set forth in claim 1, characterized in that the hoisting chamber is provided with internal guide elements for guiding the propeller assembly during the course of lifting or lowering.

55 4. An apparatus of claim 1, wherein the top section of the propeller assembly is provided with means for making it totally resistant to water.
